Design No. 3,450, dated April 27, 1869.

DESIGN FOR A TRADE-MARK

The Schedule referred to in these Letters Patent and making part of the same.

To all whom it may concern:

Be it known that I, HENRY I. BARBEY, of the city and county of New York, have originated and produced a new Design for a Trade-Mark, of which the following is a full, clear, and exact description, reference being had to the annexed drawing, making a part of this specification.

My design consists of a band or garter with buckle and double slide, with a cornice added at the foot of the oval which the garter or strap forms.

Within the width of the garter, and at the top of the oval, the words "Twelve yards, warranted," in plain block-letters, to indicate the number of yards each piece contains, to which this trade-mark is adjusted.

"A A" is specially a mark of the firm.

The monogram indicating the letters "S. & Co." represents the name of the manufacturers.

This is intended to be used as a print, or engraving, or stamp, either on paper, wood, or silk goods.

What I claim as my invention, and desire to secure by Letters Patent, is—

The design for a trade-mark, substantially as shown and described.

New York, March 25, 1869.

HENRY I. BARBEY.
